Res. 955

Smith, Henry Brown and Joseph A. Read, all of the City of Philadelphia, and State of Pennsylvania have invented or produced "a new and original design for a hall or parlor stove" and we do hereby declare that the accompanying drawing is a full, clear, and exact representation of the same.

Fig. 1. is a front elevation of the stove, without the ornaments, and drawn to a scale of one and a half inches to a foot.

Fig. 2 A. a ground plan of the hearth.

Fig. 3. B. a front view of the ash pit, and ash pit door.

Fig. 4. C. a side view of the ash pit.

Fig. 5. D. a back view of the ash pit.

Fig. 6. E. a plan view of the top of the ash pit.

Fig. 7. F. a front view of the fire door.

Fig. 8. G. a plan view of the cap of the stove.

The cap G, is connected to the top E, of the ash box by the cylindrical body b, of plate iron and by the three tubes a. a. & a'.

We claim the combination of the various ornamented plates, as shown in the drawing the whole forming a design for a hall or parlor stove, In testimony where we have signed our names to the specification
